UNITED STATES PATENT OFFICE.

JAMES MARTIN, OF NEW YORK, N. Y.

DESIGN FOR A VEHICLE-TIRE.

46,775.

Specification for Design.

Patented Dec. 15, 1914.

Application filed April 4, 1914. Serial No. 829,713. Term of patent 7 years.

To all whom it may concern:

Be it known that I, JAMES MARTIN, a citizen of the United States, residing at New York, in the county of New York and State of New York, have invented a new, original, and ornamental Design for a Vehicle-Tire, illustrated in the accompanying drawing, in which—

Figure 1 is a top plan view of a portion of a vehicle tire constructed in accordance with the invention, and Fig. 2 is a transverse sectional view through the tread portion thereof.

Copies of this patent may be obtained for five cents each, by addressing the "Commissioner of Patents, Washington, D. C."

I claim:—

The ornamental design for a vehicle tire, as shown, the tread of the tire being provided with a series of annular depressions, each annular depression being provided with a cross bar and all of the cross bars being disposed at an inclination to the axis of the tire, alternate cross bars being inclined in opposite directions.

JAMES MARTIN.
